UNITED STATES PATENT OFFICE.

FRANCIS M. CROSSLEY, OF REDFORD, MICHIGAN.

SWITCH-TONGUE-HOLDING DEVICE.

1,360,270.

Specification of Letters Patent. Patented Nov. 30, 1920.

Application filed July 2, 1920. Serial No. 393,519.

To all whom it may concern:

Be it known that I, FRANCIS M. CROSSLEY, a citizen of the United States of America, residing at Redford, in the county of Wayne and State of Michigan, have invented 5 certain new and useful Improvements in Switch-Tongue-Holding Devices, of which the following is a specification, reference being had therein to the accompanying drawings.

In my pending application Ser. No. 326,548, filed Sept. 26, 1919, there is disclosed a novel retaining member or spring construction by which a switch point or tongue may be positively held in an adjusted position, either with the switch point closed or opened, and since there is no intermediate position for the switch point, derailments are avoided. The spring construction is arranged in a suitable housing adjacent a switch mate, and for fear that the spring 15 may become weak, I have devised novel means, within the housing, for increasing the tension of the spring.

The present invention also includes novel means for correctly positioning the spring or retaining member relative to a switch point or tongue connection and means for rendering the spring or retaining member 20 inactive so that it will constitute locking means for a switch point or tongue. With my installation it will therefore be possible to lock a switch point in a set position with no danger of the switch point becoming accidentally displaced by rolling stock contacting with the same.

This invention also includes locking means and yieldable means for the arms that may be set to hold the arms against movement.

The mechanical construction entering into my invention also permits of a two-way snap switch point being converted into a one-way snap switch point, and the construction by which this and other features are attained will be hereinafter described and then claimed.

Reference will now be had to the drawings, wherein—

Figure 1 is a plan of an electric railway switch provided with a switch tongue holding device in accordance with my invention;

Fig. 2 is a horizontal sectional view of a

portion of the switch mate showing the spring housing in plan with the cover there- 55 of removed;

Fig. 3 is a cross sectional view of the same with the cover in place;

Fig. 4 is a similar view showing the arrangement for a one-way snap switch 60 tongue;

Fig. 5 is a similar view illustrating a modification of the arrangement shown in Fig. 4;

Fig. 6 is a perspective view of a detached 65 shim or spacer member, and

Fig. 7 is a plan of a housing containing a modified form of tongue holding device.

In the drawing, the reference numeral 1 denotes a conventional form of switch mate 70 having a pivoted switch tongue 2 and the switch mate 1 is slotted, as at 3, and provided with a chamber 4 for the depending lug 5 of the switch tongue 2. The side of the tongue 2 has an opening 6 communicat- 75 ing with the chamber 4 and providing clearance for a rod or slide bar 7 which is connected to the lug 5 and provided with nuts 8, spacing sleeves 9 and a double conical shaped head 10, the head 10 being interposed 80 between the confronting ends of the sleeves 9, and all of the elements held assembled on the rod 7 and fixed relative to the lug 5 by the nuts 8 on the ends of said rod.

Connected to the side of the switch mate 85 1, by screw bolts 11 or other fastening means, is a rectangular housing 12 having a countersunk detachable cover 13. In the housing 12, adjacent the outer wall thereof, is a vertical partition 14 having angularly 90 disposed end portions 15 and the partition has its upper edge provided with slots 16. In one of the slots 16 is mounted a bolt 17 having a shim or spacer member 18 and a nut 19 for holding a one piece spring or 95 resilient retaining member 20. The shim or spacer member has a concave face providing a seat for the spring 20 and said shim or spacer member is slotted, as at 21, so that it may be shifted down over the bolt 17 and 100 clamped between the spring 20 and the partition 14 by tightening the nut 19 of the bolt 17. Since the shim or spacer member 18 can be easily removed it is possible to substitute other shims for that one shown to 105 re-position the spring on the bolt 17.

The spring 20 provides opposed arms 21 having inbent portions 22 normally engaged by the head 10 on the switch tongue rod 7, and considering Fig. 2, it will be noted that the head 10 can be forced between the arms 21 to spread said arms and permit the inbent portions 22 thereof to engage the opposite side of the head 10 from that shown. The head 10 is shaped to permit of it being mounted on the rod 7 without any special attention as to it being one way or the other and there can be no intermediate position of the head 10, as its shape relative to the inbent portion 22 means that the head must pass within the spring or remain outside thereof. By placing a proper shim between the spring 20 and the partition 14 the inbent portions 22 of the arms 21 can be correctly positioned relative to the head 10, or sleeves 9 of proper length may position the head relative to the arms.

Detachably mounted in the other slots 16 of the partition 14 are take-up bolts 23 provided with nuts 24 engaging side walls of the partition 14 to hold the bolts 23 in set positions and yet permit of said bolts being completely removed. The bolts 23 engage the spring 20 and are adapted to increase the tension of the arms 21 against the head 10 of the rod 7. Should the spring 20 weaken to permit of any lost motion between the head 10 and the arms 21, it is an extremely easy matter to remove the cover 13 and adjust the bolts 23 so as to stiffen the yielding action of the arms 21 relative to the head 10.

In the operation of railways it is often necessary to lock a switch tongue, and in order that this may be accomplished I provide the bottom wall of the housing 12 with upstanding brackets or bifurcated lugs 25 for supporting bolts and nuts, generally designated 26, adapted to engage the spring arms 21 and prevent said arms from yielding when the head 10 has a tendency to move. With the bolts and nuts in position, as indicated by dotted lines in Fig. 2, it is evident that the head 10 cannot be forced between the arms 21 of the spring 20 and consequently the switch tongue 2 cannot be shifted.

The preferred form of construction provides a two-way snap switch tongue holding device and in the operation of railways it is often advantageous to use a one-way snap switch tongue so in Figs. 4 and 5 such an arrangement is provided. In Fig. 4 a head 27, similar to the head 10, serves as an abutment with the spacing sleeves 9 placed together and the abutment or head 27 placed on the rod 7 with a coiled spring 28 interposed between the inner wall of the housing 12 and the abutment 27. The expansive force of the spring 28 holds the switch tongue 2 against one wall of the switch mate 1, but rolling stock, when moving in a proper

direction, may actuate the switch tongue 2 and shift it toward the opposite wall of the switch mate, but immediately upon the rolling stock releasing the switch tongue 2, the expansive force of the spring 28 restores the switch tongue to its normal position. 70

In Fig. 5, the abutment 27, similar to the head 10, is arranged between sleeves on the rod 7 and a bolt 29 placed in the central slot 16 of the partition 14. The bolt 29 75 alines with the rod 7 and co-operates therewith in supporting a spring 30 which is interposed between the abutment 27 and the partition 14, said spring serving the same purpose as the spring 28 previously referred to. 80

Reference will now be had to Fig. 7 showing a modified form of switch tongue holding device wherein a housing 31 has ears 32 supporting pivoted arms within the housing 85 for engagement with the head 10, similar to the arms 21. In this instance the arms 33 are rigid and are maintained in engagement with the head 10 by the expansive force of springs 34 engaging the outer sides of the 90 arms 33. The springs 34 are wholly supported independent of the arms 33 on the elongated heads of bolts 36 detachably mounted in brackets or lugs 37 carried by the bottom wall of the housing 31. The tension of the springs 34 may be increased or decreased by adjusting the bolts 36 relative to the brackets 37 and the arms 33 have practically the same snap yielding action as the arms 21 relative to the head 10. This form 100 of holding device may be locked to hold the head 10 against movement by simply adjusting the bolt 36 until the elongated heads thereof bear against said arms, whereby the outer ends of said arms cannot separate to 105 allow the head 10 to pass therbetween. 95

I attach considerable importance to the fact that the construction entering into my invention permits of the holding device being easily and quickly changed to control the 110 movement of the switch tongue as may be required under different operating conditions of a railway, and since the holding device is applicable to either side of a switch mate, it is obvious that the device will meet 115 the requirements of many installations which have been heretofore served by specifically designed devices requiring a one-way installation. It will be noted that the head 10 and the spacing sleeves 9 are used when 120 converting the switch mechanism from a two way switch to a one-way switch, and it is obvious that the housing affords a container for grease or a suitable lubricant.

What I claim is:—

1. Switch tongue holding means, comprising a head movable with the switch tongue, arms forcibly engaging said head and adapted to be separated by movement of said head, and means supported wholly independent of 130

said arms for regulating the outward movement thereof.

2. Means as characterized in claim 1, wherein said arms may be locked against separation by means supported independent of said arms.

3. Switch tongue holding means comprising a head movable with the switch tongue, opposed means engaging said head and

adapted to yield to permit said head to move, and means for locking said opposed means against any yielding movement.

In testimony whereof I affix my signature in the presence of two witnesses.

FRANCIS M. CROSSLEY.
